UNITED STATES PATENT OFFICE.

ANDREW J. TICE AND CHARLES GORSUCH, OF ALLIANCE, OHIO.

CREDIT-CABINET.

No. 838,223.

Specification of Letters Patent.

Patented Dec. 11, 1906.

Application filed March 22, 1906. Serial No. 307,470.

To all whom it may concern:

Be it known that we, ANDREW J. TICE and CHARLES GORSUCH, citizens of the United States, residing at Alliance, in the county of Stark and State of Ohio, have jointly invented certain new and useful Improvements in Credit-Cabinets; and we do hereby declare that the following is a full, clear, and exact description of the same, reference being had 10 to the annexed drawings, making a part of this specification, and to the numerals of reference marked thereon, in which—

Figure 1 is a vertical section showing the cabinet open and the normal position of the credit-slip-holding leaves. Fig. 2 is a detached perspective view of the light-switch, Fig. 3 is a perspective view of one of the credit-slip-holding leaves, showing portions broken away and illustrating the bottom or under side of the leaf when in open position. Fig. 4 is an edge view of a series of credit-slip-holding leaves, showing them brought into edged position. Fig. 5 is a front view showing the various leaves in position and the cover turned back or in open position. Fig. 6 is a view of the indicating-board and its rods. Fig. 7 is a perspective view showing a portion of a credit-leaf hinge-rod and a number of hinge-bars connected thereto and the 20 different parts pertaining to said bars. Fig. 8 is a sectional view showing the hinge-leaf bar in section, also showing a credit-leaf connected thereto.

The present invention has relation to credit-cabinets; and it consists in the novel construction hereinafter described, and particularly pointed out in the claims.

Similar numerals of reference indicate corresponding parts in all the figures of the 40 drawings.

In the accompanying drawings, 1 represents the sides of the cabinet, which are spaced apart and held in proper spaced relation by means of the back 2, the bottom 3, and the cross-bar 4, which parts constitute the cabinet-case proper. It will, however, be understood that we do not desire to be confined to the exact arrangement of the cabinet, as the objects hereinafter described 45 can be carried out without reference to detailed construction. To the side members 1 is attached the frame 4, which frame is provided with a glass 5. Below the glass is lo-

cated the sliding index-plate 6. Said sliding index-plate is supported in any convenient 55 and well-known manner. At the rear of the frame 4^a is located the upwardly-inclined plate 8, which inclined plate is for the purpose of holding in proper elevation the various credit-slip-holding leaves 9, which leaves 60 when in their normal positions are located and arranged substantially as shown in Fig. 1. The object in providing the inclined plate 8 and locating the same as shown is to hold each leaf 9 in a different horizontal plane, 65 or, in other words, the rearmost leaf is held at the greatest elevation, so that the top or upper ends of the leaves will extend above each other, as illustrated in Fig. 5, and thereby better expose the number-plates 10, upon 70 which number-plates are located the proper numbers to indicate the numbers upon each credit-slip-holding leaf 9, which number-plates are in this instance numbered "20," "40," "60," "80," "100," "120," "140," and 75 "160," respectively, indicating that each particular leaf 9 is to carry twenty numbers, ten upon each side of each leaf, provided both sides of the credit-slip-holding leaves are utilized; but we prefer to use only the rear 80 side of the front leaf 9 and the front side of the back leaf. The leaves 9 are all provided with the credit-slip-holding clips 11, which are provided with number-plates 12 and the clips numbered from "1" to "10," inclusive, 85 as illustrated in Fig. 3. However, the numbering of the clips may be differently arranged, if desired, without departing from the nature of our invention. The clips 11 are held in proper position by means of the 90 rods 13 and are provided with the contact-tangs 14, which contact-tangs are for the purpose of preventing the spring-coils 15 from rotating upon the rods 13 during the time the clips are elevated at their free ends 95 for the purpose of inserting or removing credit-slips.

The various leaves 9 are provided with the flanges 16, which are for the double purpose of properly spacing the credit-slips and at the same time holding the leaves in proper spaced relation when brought into the position illustrated in Figs. 1 and 4. To each leaf 9 are attached in any convenient and well-known manner the hinge-plates 17, 105 which plates are hinged to the bars 18 and

said bars hinged to the rod or hinge-bar 19, which construction is best illustrated in Fig. 8.

For the purpose of holding the rod or hinge-bar 19 in proper fixed position with reference to the inclined plate or bottom 8 the notched pins 20 are provided, which pins are connected to the inclined plate 8 in any convenient and well-known manner and the rod 10 or hinge-bar 19 seated in the notched pins 20, as illustrated in Figs. 1 and 7. Upon the bars 18 are located the sliding bars 21, which sliding bars are provided at their inner ends with the angled portions or flanges 22, which 15 angled flanges are for the purpose of abutting against the forward faces of the credit-slip-holding leaves 9, as best illustrated in Fig. 8. At the time the flanges 22 are seated and held against the faces of the credit-slip-holding leaves 9 there can be no hinge movement as between the leaves 9 and the bars 18, but the hinge movement for the leaves 9 is upon the rod or hinge-bar 19.

For the purpose of securely holding the 25 angled flanges or portions 22 against the faces of the leaves 9 the sliding bars 21 are provided with the short hinged extensions 23, which are formed of such a length and so located that when they are pressed or 30 forced down upon the bars 18; as illustrated in Fig. 8 and also Fig. 7, they will move the bars 21 endwise by reason of the angled portions 24, formed upon the bars 18, which angled portions are hingedly connected to 35 the hinge-bar 19. The object and purpose of preventing any hinge movement of the credit-slip-holding leaves 9 as between the bars 18 and the credit-slip-holding leaves 9, is to prevent any disarrangement of said 40 leaves when placed in the position illustrated in Fig. 1 and at the same time allowing each leaf to be turned from the position illustrated in Fig. 1 down and practically parallel with the frame 4 without hiding from view any 45 portion of the leaf adjacent to the last one turned down.

It is well understood that in use a large number of credit-slips are employed or used, which credit-slips indicate and determine 50 the amount due from each customer, and in order to provide for better fire protection it is desirable to remove the credit-slips, together with the leaves, from the cabinet-case and place the same in a safe after the close of 55 business, and for this purpose it is desirable to bring the leaves into as compact relationship with each other as possible, so as to reduce the bulk, and in order to provide for this advantage it is desirable to have all of 60 the leaves brought into such a position that their ends will be parallel or in the position illustrated in Fig. 4, it of course being understood that the top ends will be parallel when their bottom ends are brought into the position 65 illustrated in said Fig. 4. In order that

provision may be made for the just above described arrangement of the various leaves, the bar or hinge-rod 19 is provided with the cross-pins 25, which cross-pins are for the purpose of lifting the hinged extensions 23, as illustrated in dotted lines, Fig. 8, and for the purpose of providing a means for permitting the pins 25 to come in contact with the hinged extensions 23 the bottom or under side of the bars 18 are cut as illustrated 75 at 26, Fig. 7.

It will be understood that after the hinged extensions 23 have been lifted or turned upon their hinged connections the sliding bars 21 are free to move endwise, and thereby 80 release the angled flanges 23 from the credit-slip-holding leaves 9, at which time there is a hinge connection as between the bars 18 and the leaves 9, which permits all of the leaves 9 to be brought into the position illustrated in Fig. 4 and in such a position that they can be placed in a compact form in a safe. It will be understood that in order to elevate or release the hinged extensions 23 it is necessary to rotate the bar or hinge-rod 90 19, which is preferably done by means of the key 27, which fits over and upon the angled portion 28 of the rod 19, and of course an opening must be provided in one or both of the side members 1 for the purpose of properly connecting the key.

For the purpose of preventing the hinged extensions 23 from being thrown too far backward the stop-bars 30 are provided, which are preferably formed integral with the 100 sliding bars 21.

For the purpose of causing the sliding bars 21 to move back and forth without displacement the slots 31 are provided, which slots are formed in the bars 18, and through 105 the slots are passed the rivets 32 and the tangs 33.

For the purpose of holding the connected portions 24 of the bars 18 in proper spaced relation with reference to each other the 110 disks 34 are provided and are located substantially as shown in Fig. 7.

In use it is frequently desirable to provide a light to properly read the credit-slips, which light is only required when any given 115 credit-leaf is brought into position to expose to view the credit-slips located thereon, and in order that this light may be brought into proper use at the proper time the circuit-breaker 35 is employed, which may be of the 120 form shown or it may be of any other desired form, inasmuch as the circuit-breaker within itself forms no particular part of the present invention except that a circuit-breaker must be employed, which is to be operated as hereinafter described. When the front or forward leaf 9 is brought into a lowered or exposed position or parallel with the frame 4, the circuit-breaker 35 is closed by means of the contact-point 36, which contact-point is 130

connected to the front or forward credit-slip-holding leaf 9 and is so located that it will close the circuit-breaker.

It is frequently desirable in cabinets of this kind to expose to view for the customers some information—as, for instance, "Please ask for your totaled account or the amount of your purchase" or "If you don't see what you want ask for it"—which information is printed upon the card or plate 37, which card or plate is elevated, when the front or forward leaf is turned down, by means of the rods 38, the pivoted levers 39, and the push-rods 40, which push-rods are so located at their top or upper ends that they will be moved downward, which elevates the rear ends of the levers 39 and moves the card forward and between the glass plates 41, and when the forward leaf 9 is brought into its normal position, or the position illustrated in Fig. 1, the card 37 moves downward by gravity.

The index-plate 6 is located directly under the glass 5 and is so arranged that it can be moved outward and the index-sheet changed from time to time.

For the purpose of convenience the file-drawer 43 is provided, which is located and arranged substantially as shown in the drawings and is of ordinary construction. The drawer 44 is provided, which is, of course, for any desired purpose.

For the purpose of holding the rear leaf and at the same time prevent any accidental displacement of the credit-slip-holding leaves 9 the button 45 is provided, which button is so arranged as to catch the upper edge of the rear leaf 9.

For the purpose of signaling at the time the leaves are turned down one of the levers 39 is provided with the spring-plate 46, which spring-plate engages the hammer-lever 47 and during its downward movement lifts the hammer-lever; but after the spring-plate is moved downward a sufficient distance said hammer-lever is released and permitted to fall upon the bell 48. For the purpose of preventing the hammer 47 from being thrown over or backward the stop-pin 49 is provided. For the purpose of preventing the leaves from being turned too far backward the stop-flanges 50 are provided, which stop-flanges are located substantially as shown in Fig. 7.

For the purpose of closing the cabinet the flexible curtain 51 is provided, which flexible curtain is operated in the ordinary manner and is of the ordinary construction common in roll-top desks.

Having fully described our invention, what we claim as new, and desire to secure by Letters Patent, is—

1. In a credit-cabinet, a case or frame, a series of credit-slip-holding leaves, means for connecting credit-slips thereto, means for

holding the leaves in spaced relationship with each other, hinge-plates connected to the series of leaves, a rod, a series of bars pivotally connected to said rod and to the hinge-plates, and slideable bars mounted upon the series of bars, each of the slideable bars being provided with an angled flange adapted to abut and clamp the credit-slip-holding leaves, substantially as and for the purpose specified.

2. In a credit-cabinet of the class described, a series of credit-slip-holding leaves, bars pivotally connected to the credit-slip-holding leaves, a rotatable bar having loosely mounted thereon the hinged credit-leaf bars, means for locking the credit-slip-holding leaves against hinge movement at their connected ends or portions and means for releasing the credit-slip-holding leaves to permit hinge movement between the bars and leaves, substantially as and for the purpose specified.

3. In a credit-cabinet, a frame, a series of credit-slip-holding leaves, a support adapted to hold said credit-slip-holding leaves in different horizontal elevations, a rod or bar having connected thereto a series of leaf-holding bars, said leaf-holding bars provided with hinged portions adapted to be secured to the credit-slip-holding leaves, and means for holding the leaves against hinge movement at points of connection with the leaves, substantially as and for the purpose specified.

4. In a credit-cabinet, a frame, an upwardly-inclined leaf-holding plate connected to said frame, a series of credit-slip-holding leaves, bars hingedly connected to said leaves, a rotatable bar detachably connected to the upwardly-inclined leaf-holding plate, sliding bars carried by the bars connected to the leaves and provided with hinged extensions, and means for moving the sliding bars, substantially as and for the purpose specified.

5. In a credit-cabinet, a series of slip-holding leaves, a rotatable bar, means for independently hinging the leaves to the bar, the leaves being hingedly connected to the means for hingedly connecting the same to the bar, and means for locking the credit-slip-holding leaves against hinge movement independent of their hinge movement upon the rotatable bar, substantially as and for the purpose specified.

6. In a credit-cabinet, a series of slip-holding leaves, normally held in different horizontal planes, said slip-holding leaves provided with number-slips and credit-holding clips provided with number-plates, bars hinged to the leaves, sliding bars carried by the bars hinged to the leaves and provided with flanges adapted to be seated against the faces of the credit-slip-holding leaves, and a rotatable bar adapted to actuate the sliding bars, substantially as and for the purpose specified.

5. In a credit-cabinet a frame, a series of leaves located therein and independently hinged, a display-card and means for elevating the display-card when one of the leaves is brought into lowered position, substantially as and for the purpose specified.

In testimony that we claim the above we

have hereunto subscribed our names in the presence of two witnesses.

ANDREW J. TICE.
CHARLES GORSUCH.
